UNITED STATES PATENT OFFICE.

FRANZ J. WEISS, OF BASLE, SWITZERLAND.

AIR-PUMP.

SPECIFICATION forming part of Letters Patent No. 314,766, dated March 31, 1885.

Application filed December 27, 1882. (No model.) Patented in England July 26, 1882, No. 3,551; in Germany November 21, 1882, No. 22,775; in France November 25, 1882, No. 150,319; in Belgium December 15, 1882, No. 43,398, and in Italy March 31, 1883, XVI, 15,049, XXX, 161.

To all whom it may concern.

Be it known that I, FRANZ JOSEPH WEISS, a citizen of the Republic of Switzerland, residing in the city and canton of Basle and Republic of Switzerland, have invented certain new and useful Improvements in Air-Pumps, of which the following is a specification, reference being had to the accompanying drawings.

This invention relates to improvements in air-pumps, and has for its object to reduce the detrimental effect of the clearance-space, or space between one end of the cylinder and the piston, when the latter is at that end of its stroke. In other words, the object is to conduct the compressed air from the clearance-space to the suction side of the piston.

The invention consists in the construction and arrangement of parts, which will be hereinafter more fully described, and then set forth in the claim.

In the drawings, Figure 1 is a longitudinal section of the cylinder, piston, and slide-valve, the figure also representing the position of the piston during its real working period, and showing a slide-valve which has ports for the outlet of the compressed air, and also carries a back-pressure valve. Fig. 2 is a view of the parts shown in Fig. 1 when the piston has completed its stroke and the channel in the slide-valve is in communication with the clearance-space at one end of the cylinder for conducting the compressed air in said space to the suction side of the piston.

The letter A in the figures designates the cylinder of an air-compressing or vacuum pump, and B is the piston, which operates therein in the customary manner. The air to be compressed or exhausted is admitted into a chamber or space, C, which is open to the external air or chamber to be exhausted. Over this air-inlet chamber is arranged a slide-valve, D, which has a central space, d, that is alternately brought into line with ports or channels F formed in the cylinder-shell and leading to the ends of the piston-chamber. The valve D is furthermore provided with a longitudinal channel, a, which has transverse end ports, d', that open out through the face of the valve moving in contact with the seat on the working-cylinder. At one side of the

valve chamber or chest is located an eduction-chamber, E, for the compressed or exhausted air, and a valve, R, carried by the slide-valve D and arranged in said chamber, serves to close the communication with said valve-chamber after the piston has completed its stroke and forced the air from the working-cylinder into the eduction-chamber. In other words, this valve is opened in an outward direction by the air passing from the cylinder, and is closed and held to its seat by the back-pressure of the air in the chamber E. The eccentric or cam for imparting motion to the slide-valve D follows the crank of the engine-shaft at an angle of about ninety degrees, and a pitman serves to connect it with the valve in such a manner that in the operation of said valve the connection of the channel and ports d with the space in front of the piston with that behind the same is effected at the medium position of the valve, as in Fig. 2. The outer and inner laps of the slide-valve are of such size that the channel a is about to be closed when the outer and inner edges of the slide-valve in their turn open the air-channels for the purpose of connecting the pressure-space with one end of the cylinder and the suction-space with the other end thereof. Moreover, if the outer and inner laps are equal and the cam or eccentric is arranged at such an angle that the outer or in turn the inner edges of the slide-valve shut off the air channels or passages exactly at the end of a stroke of the piston, then the required conditions are attained—that is to say, an effective delivery of air is caused until the piston has completed its stroke, and a connection of the spaces on each side of the piston is effected immediately after the completion of the stroke and while the pressure and suction spaces are shut off.

The valve R is employed for the purpose of enabling the piston to operate without encountering any back-pressure of the air in the eduction-chamber, and for this reason it can operate with greater freedom and with less resistance than if said valve were absent. The valve D is made sufficiently long to extend beyond the channels F, leading to the cylinder, and it has outlet-ports i and carries the back-pressure valve R, that fits over said outlet-

ports *i*. The valve R is fitted on a suitable guide-stem, S, projecting from the rear or outer face of the valve D, and a spring, T, together with the pressure of the air in the eduction-chamber, serve to hold it closed until such time as either of the ports *i* is brought opposite the passage in the cylinder through which the compressed air is being expelled by the action of the piston. In other words, when the piston is expelling the air from the working-cylinder the valve R is opened to allow the air to enter the eduction-chamber. Air-compressing or vacuum pumps constructed as above described work noiselessly and produce better effects with the same dimensions than pumps heretofore devised, such results being due to the fact that the compressed air in the clearance-space of the cylinder is at the proper time conducted into the suction-space of the cylinder, that the piston will immediately commence to suck in air when it is making its return stroke. The slide-valve also works without noise and friction.

I am aware that a valve mechanism for trip-hammers has heretofore been proposed in which a slide-valve is provided with ports that serve to establish a communication between the top and bottom of the piston and working-cylinder in order to allow a portion of the steam or other fluid which has raised

the hammer to pass from the lower to the upper side of the piston, thereby equalizing the pressure on both sides of the piston, and allowing the hammer to descend with a velocity due to gravitation alone. Such construction, therefore, I disclaim, as it forms no part of my invention, the latter relating solely to the air-compressing and exhaust pumps by which the advantages and results above set forth are obtained.

Having thus described my invention, what I claim is—

In an air-compressing or exhaust pump, the combination, with the working-cylinder, the piston, and the valve-chest having ports leading to the ends of the cylinder, and provided with an air-inlet chamber, of a slide-valve having a longitudinal channel and end ports communicating therewith, outlet-ports for the compressed air and carrying a back-pressure valve, and an eduction-chamber in which said slide-valve is located, all constructed and relatively arranged substantially as described.

In testimony whereof I have signed my name to this specification in the presence of two subscribing witnesses.

FRANZ JOSEPH WEISS.
